CLAIM

The ornamental design for a vehicle hood, as shown and described.

DESCRIPTION

FIG. 1 is a perspective view of a vehicle hood;

FIG. 2 is a top plan view of the vehicle hood;

FIG. 3 is a bottom plan view of the vehicle hood;

FIG. 4 is a left side elevational view of the vehicle hood;

FIG. 5 is a right side elevational view of the vehicle hood;

FIG. 6 is a front elevational view of the vehicle hood; and,

FIG. 7 is a rear elevational view of the vehicle hood.

Any functional features of the vehicle hood are not claimed. Views are orthogonal projections. The functional features are not claimed.
